AUTOMATIC CONTAINER TIE

Keith W. Tantlinger, Grosse Pointe Shores, and Richard T. Fujicka, Oxford, Mich., assignors to Fruehauf Trailer Company, Detroit, Mich., a corporation of Michigan

Filed Aug. 21, 1961, Ser. No. 132,619
2 Claims. (Cl. 220—1.5)

This invention relates generally to freight handling apparatus and more particularly to automatic container ties for coupling shipping containers in abutting relationship.

It is often desired to couple two or more shipping containers together to form a structurally independent assembly that accepts, for example, a fifth wheel of a conventional tractor at one end and a conventional wheel suspension at the other end. Such a container assembly and the application thereof to the aforementioned mode of transportation is fully disclosed in application Serial No. 112,635, filed May 25, 1961, for: Shipping Apparatus and assigned to the assignee of the present invention.

Often, such a pair of shipping containers must be coupled or uncoupled in the field without the use of auxiliary handling equipment. Preferably, the coupling and uncoupling operation can be accomplished by the tractor-driver working alone and in such a manner that the operation is positive yet completely safe.

The present invention provides for automatic coupling of a pair of shipping containers thereby to form a substantially rigid structural unit. Coupling and subsequent uncoupling are accomplished without requiring auxiliary equipment by novel ties that are easily conditioned for coupling or uncoupling. In addition, positive locking and safety mechanisms are automatically engaged to insure the integrity of the coupled assembly.

According, one object of the present invention is an improved automatic container tie.

Another object is an automatic container tie for transferring load between a pair of shipping containers.

Another object is a container tie that is positively engageable upon movement of a pair of shipping containers into abutting relationship with one another.

Another object is an automatic container tie that is engageable or disengageable from a pair of shipping containers without requiring auxiliary handling equipment.

Another object is an automatic container tie having integral locking means.

Another object is an automatic container tie that can be preconditioned for automatic movement to the locking or unlocking condition.

Another object is a container tie having an automatically lockable safety means for maintaining the container tie in the locked condition.

Other objects and advantages of the present invention will be apparent from the following detailed description, claims and drawings, wherein:

FIGURE 1 is a side elevational view of a pair of shipping containers in rigid coupled relationship supported by the fifth wheel of a tractor and by a conventional tandem wheel suspension;

FIG. 2 is an enlarged view of an upper container tie taken within the circle "2" of FIGURE 1;

FIG. 3 is a view similar to FIG. 2 with the container tie in the ready-to-couple condition;

FIG. 4 is a view similar to FIG. 3 with the container tie in the stored condition;

FIG. 5 is an enlarged view of a lower container tie taken within the circle "5" of FIGURE 1;

FIG. 6 is a view similar to FIG. 5 with the lower container tie in the ready-to-uncouple condition; and

2

FIG. 7 is a view similar to FIG. 5 with the container tie in the ready-to-couple condition.

Referring to FIGURE 1, a pair of shipping containers 20 and 21 are coupled in abutting relationship by upper and lower container ties generally designated by the numerals 22 and 24, respectively. The coupled containers 20 and 21 are supported at one end by a conventional fifth wheel 26 of a tractor 28 and at the other end by a conventional tandem wheel suspension 30.

10 As more particularly pointed out in the aforementioned copending application, Serial No. 112,635 assigned to the assignee of the present invention, the containers 20 and 21 are provided with a pair of pins 32 and 33, respectively (FIG. 2), that extend laterally outwardly from a pair of recessed faces 34 and 35 on the opposed upper corners thereof. This disposition of the pins 32 and 33, in combination with the automatic container ties 22 and 24 of the instant invention, renders automatic coupling and uncoupling of the containers 20 and 21 relatively easy.

15 In accordance with the present invention, the upper container tie 22 comprises a coupling arm 40 having an aperture 42 therein for the acceptance of the pin 32 on the container 20. The pin 32 is provided with an annular groove 44 therein, as is more particularly disclosed in the aforementioned copending application, for the acceptance of a pin 50 on the arm 40. The pin 50 is engageable within the groove 44 to preclude movement of the arm 40 axially with respect to the pin 32. The arm 40 is 20 freely rotatable about the pin 32 to the stored, ready-to-couple, and coupled positions, as will be described.

25 The coupling arm 40 has a reentrantly directed or gooseneck portion 52 thereon for engagement about the pin 33 on the adjacent container 21 when the containers 20 and 21 are in the abutting condition shown in FIGURE 1. The arm 40 has a downwardly depending portion 56 for the support of a rotatable locking dog 58 which is secured thereto as by a pin 60. As best seen in FIG. 3, the dog 58 is normally biased clockwise to the 30 locked position as by a spring 62. Clockwise rotation of the dog 58 is restrained by engagement of an end portion 64 thereof with an abutment 66 on the depending portion 56 of the arm 40. The dog 58 precludes counterclockwise rotation of the arm 40 with respect to its supporting pin 32, or, in other words, precludes spurious disengagement 35 of the container tie 22 from the pin 33 on the container 21, when the container tie 22 is in the coupled position shown in FIG. 2. Counterclockwise rotation of the dog 58, which is effected by simply pushing upwardly on the 40 dog 58 as by a rod 70, conditions the arm 40 for counterclockwise rotation about the pin 32. Thus, the container tie 22 is disengageable from the pin 33 on the container 21 by simply pushing upwardly on the dog 58 with the 45 rod 70 thereby rotating the arm 40 counterclockwise about the pin 32 whereupon the container tie 22 is movable to the 50 stored condition shown in FIG. 4.

55 As best seen in FIG. 3, the container tie 22 is indexed to the ready-to-couple condition by a latch 80 that is pivotally supported on a pin 82 that extends through a 60 downwardly extending portion 84 of the container tie 22. The latch 80 has a latching surface 86 that is engageable with an end face 90 of the container 20. A cam lever 100 is pivotally supported by the latch 80 on a pin 102, a lower edge face 104 of the lever 100 being 65 slideable on the corner of the container 20.

70 As the container 21 moves toward the container 20 due to, for example, backing of the tractor 28 and container 20 against the container 21, the container 21 engages an outer end face 106 of the cam 100. This biases the latch 80 counterclockwise about the pin 82, retracting the latching surface 86 of the latch 80 from

engagement with the end face 90 of the container 20 permitting the arm 40 of the container tie 22 to move clockwise so that the gooseneck portion 52 thereof engages about the pin 33. It is to be noted that movement of the arm 40 to the lock condition is positive, due to a clockwise impulse torque applied thereto upon impact of the cam 100 with the container 21 as it moves into position. The arm 40 also moves to the lock condition due to gravity. It is also to be noted that, as the arm 40 of the container tie 22 moves downwardly after release of the latching surface 86, the dog 58 is first biased counterclockwise about the pin 60, upon engagement thereof with the pin 33, permitting the gooseneck 52 to engage about the pin 33. Subsequently, the dog 58 is biased clockwise about the pin 60 by the spring 62 to the locked condition shown in FIG. 2.

As discussed in the aforementioned application, the containers 20 and 21 are provided with pins 200 and 201, respectively (FIG. 5), at the lower corners thereof that extend transversely of a pair of recessed faces 202 and 203 on the containers 20 and 21. The pins 200 and 210 accept a pair of engageable jaws 204 and 206 which comprise the lower container tie 24. The jaw 204 has an aperture 208 for the acceptance of the pin 200. The jaw 204 also has a threaded aperture 210 for the acceptance of a locking screw 212 that is engageable with the pin 200 to lock the jaw 204 thereon at a desired rotative position with respect to the pin 200. The screw 212 also precludes axial movement of the jaw 204 off the pin 200.

The jaw 204 has a gooseneck portion 214 with a latching surface 216 thereon for engagement with a complementary latching surface 218 on a gooseneck portion 220 of the jaw 206.

The jaw 206 is essentially similar in construction to the jaw 204 and has an aperture 222 for the acceptance of the pin 201 on the container 21 so as to be rotatable thereabout. The jaw 206 is restrained from axial movement with respect to the pin 201 by a slidable pin 230 that is supported in a complementary bore 232 in the jaw 206 and is acceptable in an annular groove 233 in the pin 201. The pin 230 serves a dual function, as will be described.

A function-control lever 240 is pivotally secured to the jaw 206 as by a pin 242 that is threadably engaged in a complementary bore 244. A tensioned spring 246 is secured at one end 247 to an end portion 248 of the lever 240 and at the other end 249 to the container 21 as by a bolt 250. Thus, as seen in FIG. 5, the spring 246 is conditioned to bias the jaw 206 counterclockwise about the pin 201. Rotation of the lever 240 about the screw 242 to the position shown in FIG. 6, changes the line of action of the spring 246 with respect to the axis of the pin 201 so as to bias the jaw 206 clockwise with respect thereto.

A locking block 260 is pivotally secured to the jaw 206 as by a pin 262 that is threadably engaged in a complementary bore 264 in the jaw 206. The block 260 is normally indexed to the locked position shown in FIG. 5, by a ball detent 266 that is engageable in a complementary recess 268 in the jaw 206. Rotation of the block 260 to the position shown in FIG. 6 conditions the jaw 206 for clockwise rotation under the bias of the spring 246, as will be described.

As best seen in FIG. 7, the jaw 206 is conditioned for counterclockwise rotation about the pin 201 into engagement with the jaw 204 by advancement of the pin 230 so that a head portion 270 thereof is engageable under a stud 272. In this condition, an outer end portion 274 of the pin 230 extends relatively farther out of the supporting bore 232 in the jaw 206 so that, as the containers 20 and 21 move toward one another, the end portion 274 engages the gooseneck portion 214 of the jaw 204, whereupon the pin 230 is biased to the right, as seen in FIG. 7. Upon movement of the head portion 270 of the pin 230 out from under the stud 272, the jaw 206 moves counterclockwise under the bias of the spring 246. Counterclockwise rotation of the jaw 206 brings the latching sur-

face 218 thereof into engagement with the latching surface 216 of the jaw 204 to couple the containers 20 and 21 into a substantially rigid unit. After the jaw 206 has moved into engagement with the jaw 204, the locking block 260 is rotated from the position shown in FIGS. 6 and 7 to the position shown in FIG. 5, thus precluding clockwise rotation of the jaw 206 and spurious uncoupling of the container tie 24.

To condition the container tie 24 for uncoupling, the lever 240 and block 260 are rotated to the position shown in FIG. 6.

Upon movement of the containers 20 and 21 toward one another, which is accomplished as by locking the brakes on the tandem suspension 30 and backing the tractor 28 and container 20 toward the container 21, the latching surfaces 216 and 218 are separated slightly, allowing the jaw 206 to rotate clockwise under the bias of the spring 246 to effect uncoupling of the container tie 24.

Thus, it will be seen that the container tie 24 can be conditioned for coupling or uncoupling, which operation can be effected solely by the tractor-driver by moving the containers 20 and 21 toward one another.

It is to be understood that the specific construction of the improved automatic container tie herein disclosed and described is presented for the purpose of explanation and illustration and is not intended to indicate limits of the invention, the scope of which is defined by the following claims.

What is claimed is:

1. In a shipping apparatus comprising a pair of juxtaposed shipping containers having spaced parallel pins thereon, means for coupling the containers in said juxtaposed relationship comprising an arm rotatably coupled to one of the pins and having an end portion engageable with the other of the pins to preclude relative movement of the pins away from each other in a direction generally normal to the axis thereof, and means on said arms for conditioning the end portion of said arm for automatic engagement with the other of said pins comprising a latch for holding said arm in a ready-to-couple condition and cam means engageable with the container having the other of the pins for releasing said latch to permit said arm to move into engagement with the other of the pins.
2. In a shipping apparatus comprising a pair of juxtaposed shipping containers having spaced parallel pins thereon, means for coupling the containers in said juxtaposed relationship comprising an arm rotatably coupled to one of the pins and having an end portion engageable with the other of the pins to preclude relative movement of the pins away from each other in a direction generally normal to the axis thereof, a locking dog, resilient means for normally biasing said dog to the locked position, said dog being automatically movable to the unlocked condition upon movement of said arm toward engagement with the other of said pins and automatically movable to the locked condition upon engagement of said arm with the other of said pins, and means on said arm for conditioning the end portion of said arm for automatic engagement with the other of said pins comprising a latch engageable with the container supporting said one pin for holding said arm in a ready-to-couple condition and cam means engageable with the container having the other of the pins for releasing said latch to permit said arm to move into engagement with the other of the pins.
